UNITED STATES PATENT OFFICE.

CHARLES E. YETMAN, OF OAKPARK, ILLINOIS, ASSIGNOR TO WORLD FLASH COMPANY, OF CHICAGO, ILLINOIS, A CORPORATION.

TYPE-WRITING MACHINE.

SPECIFICATION forming part of Letters Patent No. 760,719, dated May 24, 1904.

Application filed September 26, 1900. Renewed March 18, 1904. Serial No. 198,835. (No model.)

To all whom it may concern:

Be it known that I, CHARLES E. YETMAN, a resident of Oakpark, in the county of Cook and State of Illinois, have invented certain new and useful Improvements in Type-Writing Machines, of which the following is a full, clear, and exact description.

This invention has relation to that class of type-writing machines in which the paper to be printed upon is supported upon a platen mounted upon a carriage adapted to move transversely with the machine, the movements of the carriage being effected through suitable escapement mechanism controlled by the manipulation of the key-levers whereby the type-bars are operated.

In the accompanying drawings the invention is shown as applied to that class of type-writing machines now commonly known as "visible" type-writers, although many features of the invention will be found applicable to type-writing machines of other kinds.

The invention consists in the various features of improvement hereinafter described, illustrated in the accompanying drawings, and particularly pointed out in the claims at the end of the specification.

In the drawings the invention is shown as applied to a type-writing machine certain features of which are embodied in applications filed by me in the United States Patent Office of even date herewith and bearing Serial Nos. 31,198 and 31,200, and I do not wish to be understood as claiming herein the features specifically claimed in such companion applications.

Figure 1 is a view in elevation of the right-hand end of the machine. Fig. 2 is a view in elevation of the left-hand end of the machine. Fig. 3 is a view in vertical longitudinal section (from front to rear) of the machine. Fig. 4 is a detail view, in horizontal section, through the bearing of the carriage-retracting lever at the right-hand side of the main frame. Fig. 5 is a view in vertical longitudinal section from front to rear through the main frame of the machine adjacent one side thereof, showing the carriage-retracting lever and certain parts connected therewith. Fig. 6

is a detail view, in horizontal section, through 50 the mechanism shown at the right hand of Fig. 5 for adjusting the tension of the carriage-retraction spring. Fig. 7 is a detail front view of the paper-carriage and parts sustained thereby. Fig. 8 is a detail front 55 view of one of the journal-brackets for the front presser-rolls of the paper-carriage. Fig. 9 is a detail back view of one of the paper-guide fingers and the plate extending upward therefrom. Fig. 10 is a detail back view of 60 the paper-carriage and parts sustained thereby. Fig. 11 is a detail plan view of the paper-carriage frame, parts being broken away. Fig. 12 is a view in vertical section on line 12 12 of Fig. 7. Fig. 13 is a view in vertical 65 section on line 13 13 of Fig. 7. Fig. 14 is a view in vertical section on line 14 14 of Fig. 18. Fig. 15 is a detail plan view of the escapement ratchet-wheel, the dogs adjacent thereto being shown in section on line 15 15 of Fig. 70 14. Fig. 16 is a detail front view of the escapement mechanism, certain adjacent parts being shown in vertical section. Fig. 17 is a detail side view of the escapement-dogs, the shaft whereon the dogs are mounted being 75 shown in cross-section. Fig. 18 is a plan view of the carriage-operating mechanism, parts being shown in section and the top of the main frame being removed. Fig. 19 is a view in vertical longitudinal section (from 80 front to rear) adjacent the upper-case lever at the left-hand side of the machine, parts being shown in elevation. Fig. 20 is an enlarged detail side view of the platen-shifting mechanism, parts of the main frame, the carriage, and the platen being shown in vertical cross-section. Fig. 21 is a detail front view of the platen-locking mechanism, the adjacent side wall of the main frame being shown in section. Fig. 22 is a view in central vertical 90 section through the parts shown in Fig. 21. Fig. 23 is a detail view in vertical cross-section through the crank and shaft shown at the right-hand side of Fig. 22, adjacent parts being in elevation. Fig. 24 is a view in vertical section on line 24 24 of Fig. 22. Fig. 25 is a view similar to Fig. 24, but showing the parts in different position. Fig. 26 is an 95

end elevation of the paper-carriage and parts sustained thereby.

In the accompanying drawings the invention is shown as embodied in a machine having a main frame or casing comprising a base portion A and an upper portion A', upon which latter the carriage is sustained.

The finger-keys B are pivoted at their rear ends to a transverse bar 3 and extend forwardly to the keyboard of the machine. Transverse bar 3 is sustained from a transverse bar 2. The key-levers B are provided with upwardly-extending offsets b', to which are connected springs 5, which serve to hold the key-levers in their normal uplifted position. Supplemental upright levers C are pivoted at their lower ends, as at c, to the transverse bar 5. The uprights or offsets b' of the key-levers B have pin-and-slot connections c' with the supplemental levers C. Type-bars D are pivoted to suitable hangers D', which are held in place by a bolt 10 upon a semicircular step-support D''. The inner ends of the type-bars D are connected to the supplemental levers C by suitable links. In Fig. 3, for the sake of clearness, only a single type-bar and its operating connections are shown. It will, however, be understood that the type-bars are grouped in semicircular series about the printing-point on platen W in the manner usual with type-writers of the visible "front-strike" type. The arrangement of key-levers, supplemental levers, and type-bars form no part of the present invention, but are fully described and claimed in a companion application, Serial No. 31,198, filed of even date herewith.

Across the front of the machine is a rack A² for holding the stenographer's note-book, &c. This rack is provided with an upturned lower edge a' and bent brackets a'', by which it is supported from the top of the machine, being secured thereto by thumb-screws a³. The heights of the parts A and A' of the machine are so proportioned that this rack may be located, as shown, directly before the eyes of the operator without obscuring either the keyboard or the printed line, and I believe that I am the first to construct a copy-holder of this sort. Across the top of the upper portion A' of the main frame extend the carriage-tracks 50 and 51, between which are placed the rails 52 and 53 of the carriage J. The carriage-tracks 50 and 51 and the carriage-rails 52 and 53 are provided upon their opposing faces with suitable grooves to receive the antifriction-balls 54, stops being provided to prevent the passage of the balls from out their grooves. The rear track 51 of the paper-carriage (see Fig. 14) will be mounted upon the main frame in such manner that it may be adjusted by means of set-screws at its rear in order to compensate for any wear in the bearings; but as this forms no part of the

present invention it need not be more particularly described.

The paper-carriage J is preferably formed as a casting, comprising the front and rear walls 52 and 53, the central web j, and arched end plates j' and j'', and between the arched end plates the platen W and coöperating parts will be sustained. To the under side of the front carriage-rail 52 and extending lengthwise thereof is secured a rack-bar 55, with which engage the teeth of the gear-wheels 56 and 57. These gear-wheels are mounted upon a shaft 58, (see Figs. 3 and 18,) one end of which is shown as journaled in a bracket 59, while the opposite end is journaled in a threaded bearing projecting inwardly from a boss or offset 60 at the back of the main frame. The gear-wheel 56 is loose upon the shaft 58; but the gear-wheel 57 is fixed thereto, and to this shaft 58 is also fixed a beveled gear 61, upon the rearwardly-extending hub of which the gear-wheels 56 and 57 are preferably mounted. The beveled gear 61 meshes with the corresponding beveled gear 62, that is fixed to a cross-shaft 63. The cross-shaft 63 has its inner end journaled in the bracket 59, and its opposite end is journaled in a suitable bearing at the right-hand side of the main frame of the machine. A set-nut 64 upon the shaft 58 serves to hold the gear-wheels 56 and 57 in position upon the shaft. On the shaft 63 is fixed a pinion 65, with which engages a segment-rack 66, (see Fig. 5,) that is carried at the inner end of a plate 67, fixed to or formed in piece with a rock-shaft 68, that is journaled in the side wall of the main frame. The outer end of the rock-shaft 68 has connected thereto a crank-handle 69, that extends forwardly at the right-hand side of the machine and within easy reach of the operator's hand. The plate 67 is shown as formed with a suitable cam-shaped or curved surface 70, over which passes the carriage tape or cord 71, the inner end of this tape or cord being conveniently fastened, as at 72, to the plate 67. The tape or cord 71 passes downward beneath a friction-roll 73 and is connected to the inner end of a coil-spring 74. The opposite end of this coil-spring 74 is attached to an arm 75, (see Figs. 5 and 6,) the upper end of which is formed with a threaded hole through which passes an adjusting-screw 76, whereby the arm 75 may be moved forwardly or rearwardly in order to adjust the tension of the coil-spring 74. The screw 76 passes through a hole formed in the angular plate 77, that is attached, as by the screws 78, to one side of the main frame, an opening being formed in the front of the main frame to expose the head of the screw 76, so that it may be conveniently adjusted by the operator. It will thus be seen that by turning the screw 76 the operator can vary the tension that the spring 74 exerts upon the tape 71 and upon the carriage. The purpose of the hand-lever

69 is to enable the operator to readily shift the carriage in forward or backward direction, the handle being especially advantageous for quickly shifting the carriage to the right in 5 order to begin a new line of print, and by reference to Figs. 1, 5, and 18 it will be seen that if the handle 69 be in the position there shown and the operator depresses the handle it will rock the shaft 68 and turn upwardly 10 to the segment-rack 66, which in turn will impart partial revolution to the pinion 65 and shaft 63 and through the medium of the beveled gear-wheels 62 and 61 will impart partial revolution to the gear-wheels 56 and 57. Inasmuch as these gear-wheels are in constant engagement with the rack-bar 55, attached to the under side of the carriage, it is manifest 15 that as the handle 69 is thus depressed the movement of the carriage from left to right will be effected, the extent of this movement 20 depending upon the amount of depression given to the handle.

With the loose gear-wheel 56 meshes a pinion 80, that is mounted upon a counter-shaft 25 81, (see Figs. 14, 16, and 18,) one end of this counter-shaft being journaled in a bracket 59, bolted to the side wall of the main frame, while the opposite end of this shaft is journaled in a threaded bearing-block 83, that is 30 fastened to the inner end of a boss or inward extension 84 on the back plate of the main frame. The gear-wheel 80 is connected to or formed in piece with a sleeve 85, that is loosely mounted on the shaft 81, one end of this 35 sleeve being formed with clutch-teeth 86, that engage corresponding teeth 87, formed upon the hub of a worm 88, that is fastened to the shaft 81. The clutch-teeth 86 and 87 are forced normally into engagement by a coil-spring 89, that is mounted on the shaft 81, 40 one end of the spring setting within an annular recess of the sleeve 85, while the opposite end of the spring bears against a washer 90, that is mounted on the shaft 81. Between 45 the washer 90 and a threaded nut 91, also on the shaft 81, is held the escapement-wheel K, having teeth k, adapted to be engaged by the escapement-dogs L and L', to be presently described.

50 In any type-writer in which the movement of the paper-carriage is controlled by a propelling spring or weight and by an escapement connected to the carriage through the medium of a gear-pinion and carriage-rack it is necessary that the propelling-spring shall be free to exert its pull upon the carriage to take up the play or backlash between the teeth of the carriage-rack and the teeth of the escapement-pinion. If the carriage were not 55 so held, it could move loosely backward and forward on its bearings to the extent of the backlash between the teeth of the rack and the escapement-pinion. This movement would of course affect the spacing of the printed 60 characters and render the operation of the

machine defective. In the usual construction the propelling-spring is directly connected to the carriage; but in the present construction the propelling-spring is connected through the segment 66 and the train of gears 65, 62, 61, 70 75 and 57 and rack 55. It is, nevertheless, necessary that the propelling-spring should be able to exert a direct pull upon the paper-carriage. If, for example, the fixed gear 57 engaged directly with the escapement-pinion 80, omitting the loose gear 56, the gear 57 would be held rigidly in position by the escapement mechanism and the carriage would be free to move back and forth to the extent of the backlash between such gear 57 and the carriage-rack 55, since with such a construction the propelling-spring would not be free to exert a direct pull upon the carriage; but, however, by providing the loose gear 56, engaging the teeth of the escapement-pinion 80 80 85 and the teeth of the carriage-rack 55, the propelling-spring and the escapement will be connected to the carriage by independent gear-trains. With this construction it is clear that the propelling-spring is free to exert a pull to hold the carriage toward the left, while the escapement, through the gears 80 and 56, operates to hold the carriage to the right. In other words, the loose gear 56 engages the carriage-rack 55 to hold the carriage in position, while the gear 57 is free to engage the rack to move the carriage forward and take up the backlash between the teeth of the rack and the teeth of the gear 56—that is to say, the teeth of the rack are locked between the 90 teeth of the loose gear-wheel 56 and the teeth of the tight gear-wheel 57.

By reference to Figs. 14 and 18 of the drawings it will be seen that the teeth 86 and 87 of the clutch are so inclined that when the gear-wheel 80 is turned in one direction the teeth will interlock and impart revolution to the shaft 81 and to the escapement-wheel K; but when the gear-wheel 80 is turned in the opposite direction the inclined faces of the teeth 86 will ride over the corresponding inclined faces of the teeth 87, the spring 89 allowing the sleeve 85 to yield for this purpose. When the paper-carriage J is moved in backward direction through the medium of the hand-lever 69, as above described, or in any other manner, the gear-wheel 80 is turned by the gear-wheel 56; but during this backward movement of the carriage the teeth 86 ride over the teeth 87 in manner last described 110 115 without effecting the movement of the shaft 81.

The worm 88 meshes with the teeth of a worm-wheel 93 upon the shaft 94, this shaft serving to sustain the ribbon-spools and operating mechanism, which form no part of the 120 present invention, but are embodied in an application filed by me of even date herewith. The escapement-dogs L and L' are preferably formed in piece with or suitably connected to a split sleeve or collar 100, (see Figs. 14, 16, 130

and 17,) that is fixed to a short shaft 101, the inner end of this shaft being journaled in a bracket 102, secured to track 50, while its opposite end is journaled upon a bearing-screw 103, projecting inwardly from one side of the main frame. On one end of the shaft 101 is fixed a stop-arm 103^a, adapted to contact with a stop 103^b, that projects inwardly in the path of the arm, and thus limits the movement of the shaft 101. The shaft 101 has fixed thereto a collar 104, provided with a crank-arm 105, to which is connected the upper end of a link 106, the slotted lower end of this link (see Fig. 14) being connected to the upper arm 107 of the bell-crank that is mounted upon the shaft 108, which extends from side to side of the main frame and is journaled on suitable bearing-screws at its ends. Each end of the shaft 108 has fixed thereto a depending crank-arm 109, the crank-arm shown at the left-hand side of the machine being preferably in piece with the hub of the crank-arm 107, and each of the crank-arms 109 are pivotally connected, as at 110, with links γ^3 , that lead inwardly from the upwardly-extending portions of the universal bar G. The bail or universal bar G is pivoted to the support for key-levers and extends forwardly, as shown in Fig. 3, beneath such key-levers, is upheld by springs in the manner already described with reference to the key-levers, and is provided with an upwardly-projecting portion, as shown in Fig. 19, which is connected to the crank-arm 104. The escapement-dogs L and L' are drawn to their normal position by means of a coil-spring 112, one end of which is connected to the stop-arm 103^a, while its opposite end is connected to a threaded rod 113, that passes through the back plate of the main frame and is there provided with an adjusting thumb-nut 114. In Fig. 15 of the drawings the escapement-dogs L and L' are shown in their normal or idle position with respect to the escapement-wheel K. If now the universal bar be rocked, as by the depression of a key-lever or of the space-bar, so as to move forwardly the connecting-links γ^3 in the direction of the arrow, Fig. 14, the dog L will pass from engagement with the pointed end of the adjacent tooth k of the escapement-wheel K. Now inasmuch as the escapement-wheel is connected, through the shaft 81, the gear-wheel 80, the gears 56 and 57, the beveled gears 61 and 62, shaft 63, and gear-wheel 65, with the rack and plate 66 and 67, to which the carriage-retracting tape 71 and spring 74 are attached, it will be seen that there is a constant tendency of the escapement-wheel to turn in the direction of the arrow shown in Fig. 15. Hence when the dog L is swung transversely to the plane of movement of the ratchet-wheel K by the rocking of the shaft 101, so as to clear the point of the adjacent tooth k, the escapement-wheel K will turn in the direction of the arrow, Fig. 15, and the

tooth k will pass through the space between the points of the dogs L and L' as the dogs swing in opposite direction upon the release of the universal bar. As soon, however, as the universal bar is thus released the dog L is restored to the normal position, (seen in Fig. 15,) and as the adjacent tooth k of the escapement-wheel has passed between the dogs the next succeeding tooth of the wheel will be caught by the point of the dog L. Heretofore the dog L has been formed upon one side with a beveled face and upon its opposite side with a face parallel with the plane of movement of the dog, and the teeth k of the escapement-wheel have been formed upon one side with beveled faces and upon the opposite side with faces at exactly right angles to the plane of the wheel—that is to say, in previous constructions the bearing-faces of the dog L and the teeth k which are normally in contact at the end of the letter-space movement are arranged parallel to the movement of the dog L, while as in this instance the end of the dog L and the side of the teeth k which are in engagement with the end of the dog L as the teeth k pass between the escapement-dogs L and L' are beveled or inclined, so that the springs connected to the escapement-dogs will be brought into play to cam or force the members of the escapement rapidly past each other. I have found that with such prior construction when the universal bar was released and a tooth k of the escapement-wheel struck the opposing face of the dog L there was a tendency of the wheel to rebound and in so doing to slightly spring and force laterally the dog L, so as to permit the tooth to pass between the dogs, and thus sometimes fail to promptly arrest the carriage. By reference to Fig. 15 it will be seen that the dog L and teeth k have their opposing faces, which are in engagement at the end of the letter-space movement, slightly inclined—that is to say, the bearing or normally contacting face of the dog L is inclined to the plane of movement of the dog, while the bearing or normally contacting faces of the teeth k are correspondingly inclined slightly to the plane of movement of the wheel. Hence when the teeth k strike the bearing-face of the dog L there is a tendency of the dog and teeth to interlock, so as to prevent the accidental slipping of the dog from engagement with the point of the tooth—that is to say, the normally opposing faces of the teeth k and the dog L, which are in contact at the end of the letter-space movement, are so inclined that the carriage-propelling spring, which normally urges the ratchet-wheel K in forward direction, is brought into play to cam or lock the escapement members together at the end of the letter-space movement. In practice I have found that a comparatively slight inclination of the opposing or normally contacting faces of the dog L and of the teeth k is very effective in preventing the accidental disengagement of

the dog and teeth and consequent "skipping" of the carriage, and with this construction it also becomes possible to hold the escapement-wheel by a very slight interlock of its teeth with the dog, and hence the dog will respond more quickly to the action of the key-levers. It will thus be observed that not only the end of the dog L but its bearing face or side is inclined or beveled to the plane of its movement, so that the dog has two working intersecting faces which are so inclined, and not only the side of the teeth k , but its bearing-face, is correspondingly inclined, so that the teeth k have two working faces which intersect and which are inclined to the plane of movement of the dog. Moreover, it will be observed that the universal bar G operates the dogs through a lost-motion connection, since the pin on the arm 107 engages a slot in the link 106 and is normally positioned centrally in the slot, so that the dogs are not operated until the universal bar has been depressed to some extent and are at rest before the universal bar returns to its normal position. In this way the operation of the escapement is extremely rapid, while at the same time the vibration of the universal bar after it has been depressed and returned to normal is not transmitted to the escapement-dogs, so that there is no danger of a double operation of the escapement. Many type-writers have this fault of skipping in this way, and I have used this simple means to prevent it in this machine.

Between the end bars j' and j'' of the carriage J extends a rocker-plate M, that is pivoted, as at m , to the end bars of the carriage and has its inner edge formed with the usual notches to receive the adjustable margin-stops, bell, &c. To the rocker-plate M adjacent the left-hand end is attached a bracket M' , having an angular portion M^2 , that extends through a hole j^3 , formed in the end plate of the carriage, this angular portion being furnished with a finger-piece, whereby it may be conveniently manipulated by the operator. To the under side of the rocker-plate M at its center (see Fig. 14) is connected a depending arm 120, that carries at its lower end a friction-roll 121, adapted to travel in front of a carriage-release bar 122, that extends from side to side of the main frame, this bar having downwardly-turned ends 123, that are pivoted, as at 124, to the side walls of the main frame. The lower end of one of the arms 123 of the release-bar is extended downwardly considerably below its pivot-point and is bent inwardly and attached to a sliding yoke-frame 125, (see Fig. 18,) that is mounted in manner free to slide upon a short shaft 126, that projects inwardly from a boss or offset 84 at the back of the main frame. Upon this shaft 126 is a coil-spring 128, one end of which engages a stop 129 on the shaft, while the other end of the spring engages one end of the yoke-frame 125, the spring serving to hold the yoke-

frame in the position seen in Fig. 18. From the yoke-frame 125 extends inwardly a yoke-arm 130, that partially encircles the clutch-sleeve 85 and bears against the gear-wheel 80. (See Fig. 14.) Hence it will be seen that whenever it is desired to manually shift the carriage in either direction without the operation of the finger-keys or of the carriage-shift lever above described the operator can readily accomplish this by drawing forward the finger-piece at the end of the bracket M' , (see Figs. 14 and 20,) thereby causing the rocker-plate M to turn about its pivots and in so doing to cause the arm 120 to engage and force rearwardly the release-bar 122, which in turn will cause the yoke-frame 125 to be shifted upon the shaft 126 in such manner as to force the clutch-teeth 86 from engagement with the clutch-teeth 87. When the clutch-teeth are thus disengaged, the carriage may be manually shifted in either direction without imparting revolution to the shaft 81 or to the ribbon-feeding mechanism driven therefrom.

The platen W (shown in Fig. 20) is mounted upon a shaft w , that is journaled in the end bars 135 and 136 of the platen-frame, and to the shaft w are pivotally connected the platen-supporting arms 137, that are pivoted, as at 138, to the vertical end plates j' and j'' of the carriage. By reference to Figs. 1 and 26 it will be seen that the end bars of the platen-frame are provided with offsets 139, through which pass set-screws 140, the ends of these set-screws being adapted to contact with lugs j^4 at the top of the end plates of the carriage, so as to accurately determine the normal position of the platen. The end bars 135 and 136 of the platen-frame are connected together by rods 142 and 143, that extend above and below the platen.

In order to effect the shift of the platen W to enable either one of the two types carried by each of the type-bars D to be brought to the printing-point, the mechanism next to be described is provided. To the ends of the lower front rod 143 of the platen-frame are pivotally connected, as by screws 147, the upper ends of the crank-arms 148 and 149, that project forwardly from a rock-shaft 150, that extends from end to end of the carriage and is journaled at the base thereof. (See Fig. 20.) Centrally upon this rock-shaft is mounted a depending arm 151, that carries at its lower end a friction-wheel 152, the periphery of which is adapted to travel along and in front of a shifter-plate P, that extends from side to side of the main frame and is pivoted thereto, as at 154. Preferably the lower portion of the shifter-plate P is formed with a longitudinal groove p , wherein the wheel 152 will travel. By reference to Fig. 18 of the drawings it will be seen that the left-hand end of the shifter-plate P is provided with an arm or extension p' , to which is connected a

depending crank-arm p^2 , and the lower end of this crank-arm p^2 has pivotally connected thereto, as at p^3 , (see Fig. 20,) the rear end of a link 158, the forward end of which link 5 is pivotally connected to a crank-arm 159 of a short shaft 160. (See Fig. 22.) This shaft 160 is journaled in a bracket a^5 , bolted to the inner face of the side wall of the main frame. Extending outwardly from the end of the 10 shaft 160 is a short shaft 161, that extends through the side wall of the main frame, being journaled in a suitable bearing therein. Upon the shaft 161 are fixed the crank-arm 162 and the stop-arm 163, the stop-arm being 15 adapted to contact with the pin 164, whereby the link 158 is pivoted to the arm 159. (See Figs. 21 and 25.) To the upper end of the crank-arm 162 is pivotally connected, as at 20 165, the upper arm of a yoke-bar R, the lower arm of this bar having connected thereto one end of a coil-spring R' , the opposite end of which spring is suitably attached to the main frame. The stop-arm 163 is in the same vertical plane as the yoke-bar R and is adapted to 25 engage therewith when the parts are in the normal position seen in Fig. 24—that is to say, in the position which the platen will occupy when lower-case letters are to be printed. The outer end of the shaft 161 has fixed thereon to a thumb-wheel 169, whereby the shaft may 30 be manually turned for the purpose to be presently explained. The inner end of the shaft 160 has connected thereto a crank-arm 170, the connection between the shaft and 35 crank-arm being effected by means of a pin 171, that passes through a slot 172 in the hub of the crank-arm. (See Fig. 23.) To the lower end of the crank-arm 170 is connected by a pin-and-slot connection the upper end of 40 the vertical arm 173 of the upper-case key-lever. By reference more particularly to Figs. 20 to 25 of the drawings it will be seen that when the parts are in the normal position shown in Fig. 20 the tendency of the spring 45 R' is to hold them in such position. If now, however, it is desired to print upper-case letters, the platen W must be raised, and to effect this the upper-case key-lever will be depressed in the usual manner. This depression 50 of the upper-case key-lever will rock forwardly the vertical arm 173 and cause the crank 170 to turn the shaft 160 in the direction of the arrow, Fig. 23. As the shaft 160 is thus turned it will rock forwardly the crank 55 159, thereby causing this crank, through the medium of the link 158 and the crank p^2 , to swing forwardly the shifter-plate P. This forward swing of the shifter-plate will through the medium of the roller 152 and arm 151 60 rock the shaft 150, thereby causing the arms 148 and 149 to lift the platen-frame and platen from the normal or lower-case position to the position at which upper-case letters will be printed. Inasmuch as the shaft 160 is disconnected from the shaft 161 and the crank-

arms carried thereby, it is manifest that this movement of the shaft 160 will not affect the shaft 161 or its cranks. When, however, it is desired, as is often the case, to retain the platen in the upper-case position during the 70 printing of considerable matter, this will be accomplished by the operator turning the thumb-wheel 169 in such manner as to cause the crank-arms 162 and 163 to swing from the normal position (seen in Fig. 24) to the 75 position shown in Fig. 25 of the drawings. When the shaft 161 is thus turned, the upper end of the crank 162 will swing rearwardly and the crank 163 will swing forwardly, thereby striking the pin 164, and thus drawing forwardly the link 158, so as to cause the platen W to be raised to the upper-case position, as above described. The rearward movement of the crank 162 is sufficient to bring the yoke R to the position seen in Fig. 25, 80 and in such position the coil-spring R' will exert its force to hold the parts in such position; thereby retaining the platen elevated for the printing of upper-case letters. By reason of the pin-and-slot connection (shown in 85 Fig. 23) between the shaft 160 and the crank 170 it will be seen that when the crank 159 is shifted by turning the thumb-wheel 169, as just described, the pin 171 will move along the slot 172 and will not disturb the crank 90 170 nor the arm 173 of the upper-case key-lever. When the platen W is to be restored to normal position, the operator will reversely turn the thumb-wheel 169, so as to bring the parts again to the position seen in Fig. 24. 100

In order to cause the platen W to be shifted from normal to upper-case position by the easy touch of the operator of the upper-case key-lever, I have provided springs for counterbalancing the weight of the platen and its 105 frame. By reference to Figs. 1 and 26 of the drawings it will be seen that to each end of the carriage J is connected, as at s, a plate-spring S, that is curved around the carriage and has its free end bearing against the screw-heads 147 at the end of the lower cross-bar of the platen-frame. The force of these springs is such as to counterbalance in great measure the weight of the platen and its frame, so that these parts may be lifted with but slight effort by the shifting of the upper-case key-lever or by turning the thumb-wheel 169, as 110 hereinbefore described. 115

The lower front bar 143 of the platen-frame is revoluble in its bearings and is provided at 120 its ends with the usual springs (not shown) that serve to turn this bar downwardly and inwardly; but as this feature forms no part of the present invention it need not be more fully described. Upon the front rod 143 (see Fig. 7) 125 and at each side of the collars t, that are fixed to the rod 143, are pivotally mounted the yoke-shaped ends of the arms t', that extend rearwardly beneath the platen and (see Figs. 7, 10, 12, and 13) have their upper ends provided 130

with journal-bars t^2 , whereon are mounted the presser-rolls T, these rolls being held in position by means of set-screws t^3 or in any other convenient manner. Suitable springs 5 T' are attached to the collar t and have their free ends extending rearwardly and bearing against the arm t' , so as to lightly force the rollers T against the platen W or the paper carried thereby. The presser-rolls T extend 10 through openings u , formed in the lower section U of the paper-table. This section U of the paper-table is fixed to the arms u' , and it extends downwardly beneath and upwardly in front of the platen W, as clearly shown in 15 Figs. 7, 12, and 13 of the drawings. The arms u' are provided with hubs u^2 , that encircle the lower platen-rod 143 and are held in position upon the rod by the collars 190. The upper front edge of the section U of the 20 paper-table is provided with the usual scale u^3 , the spaces of which correspond to the escapement movement of the carriage. From the front rail 52 of the carriage extend upwardly and rearwardly suitable sockets (see Fig. 12) 25 that receive the ends v of the standards V, (see Fig. 10,) to the upper ends of which is fastened the upper section U' of the paper-table. The adjoining edges of the upper and lower sections U and U' of the paper-table 30 are formed of irregular outline, as shown in Fig. 10, and these edges are bent rearwardly, as shown at u^4 , so that all danger of the paper being caught by the edges of the table is avoided. For like reason also the upper and 35 lower edges of the cut-away spaces u of the paper-table section U are bent rearwardly, as shown. By the use of the long paper-table I have found that the paper need not be guided into the machine with one hand while the cylinder 40 is being turned with the other, as in other machines. The paper will drop to its proper place by its own weight and will guide itself much more evenly than by the other method. This is a very desirable feature, 45 since it enables the operator to insert paper in the machine very quickly. By dividing the paper in two parts, the larger part of which is fixed to the carriage, I avoid the necessity of lifting this larger part with the platen when 50 the upper case is used, the weight of which would materially detract from the light touch, which is a great advantage. On the left-hand end portion of the front platen-rod 143 is fixed the hub 195 of a lever 196, this lever being 55 provided with a finger-piece 197, (see Figs. 2 and 7,) whereby the lever may be easily manipulated, and by pushing rearwardly this finger-piece the lever 196 will turn the rod 143 against the force of the springs (not shown) at 60 its ends and in so doing will turn the collars t' , so as to relieve the force of the springs T' on the presser-rolls T. It is often desirable to ease the pressure of the rolls, particularly in the adjustment of the paper upon the platen,

and the means last described enables this to be 65 readily done.

Upon the upper rod 142 of the platen-frame are adjustably mounted the upper presser-rolls X, that are journaled between the arms of a casting x , (see Fig. 7,) from which casting project laterally studs that are journaled in the lugs y of a bearing plate or bracket Y. (See Fig. 8.) This bearing-plate Y is bolted to the downwardly-turned upper portion of a spring or clamping-plate 200, the rear portion 70 of this spring passing down and against the cross-rod 142 and being provided with an offset 201, adapted to engage a longitudinal groove in the rod. (See Fig. 12.) The spring 200 has its upper front portion formed with 75 a tongue 202, adapted to bear against an offset or lug x' on the casting x , this tongue 202 serving to force the roller X downward and against the surface of the platen W or the paper carried thereby. The rear portion of each of the 80 springs 200 passes downwardly behind the corresponding presser-roll X and is cut away to permit the presser-roll to pass therethrough, and each of the springs or clamping-plates 200 has its lower edge extending to and preferably 85 slightly over the scale u^3 at the front of the platen. So, also, each of the springs or plates 90 200 are provided with inwardly and upwardly extending guide-fingers 204, that serve to aid in guiding the paper around the platen and to 95 hold it smoothly thereon. By reference to Fig. 7 it will be seen that each of the castings is provided with an offset handle x^3 , whereby the rolls X may be turned upwardly and away 100 from the platen, and when the rolls are thus turned the lugs x' of each of the castings x will interlock with the spring-tongue 202 and retain the rolls X in such upturned position.

Having thus described my invention, what I claim as new, and desire to secure by Letters 105 Patent, is—

1. In a "front-strike" type-writing machine, the combination with a main frame comprising a base and an upright portion at the rear of said base portion, of a paper-carriage and platen mounted at the rear on said upright portion, type-bars arranged about a printing-point upon the front side of said platen, a scale arranged adjacent said platen and below said printing-point, finger-keys arranged to operate said type-bars and to form a keyboard at the front of said base portion and an inclined copy-holder mounted at the front of said upright portion, directly above said keyboard and intermediate the latter and said platen, the parts being so arranged that the printed line, the scale, the copy-holder and the keyboard are positioned directly in front of and within the visual range of the operator. 115

2. In a type-writing machine, the combination with a power-propelled part and with an escapement mechanism therefor comprising 120

- interengaging members, of means for bringing the propelling power into play to lock the members of the escapement in their interengaged position at the end of the letter-space movement. 5
3. In type-writing machines, the combination with a power-propelled paper-carriage and with an escapement mechanism therefor comprising interengaging members, of means 10 for bringing the propelling power into play to force the members of the escapement into their normal interengaged position at the end of the letter-space movement and to lock the same therein. 15
4. In type-writing machines, the combination with a power-propelled paper-carriage and with an escapement-rack therefor, of a member engaging the teeth of said rack and movable in a plane at right angles to the plane 20 of movement of said rack, the face of said member in engagement with said rack-teeth at the end of the letter-space movement being inclined with respect to the plane of movement of said member. 25
5. In type-writing machines, the combination with a power-propelled paper-carriage and with an escapement-rack therefor, of a member engaging the teeth of said rack and movable in a plane at right angles to the plane 30 of movement of said rack, the faces of said teeth in engagement with said member at the end of the letter-space movement being inclined with respect to the plane of movement of said member. 35
6. In type-writing machines, the combination with a power-propelled paper-carriage and with an escapement-rack therefor, of a member engaging the teeth of said rack, the faces of said rack-teeth and of said member in 40 engagement at the end of the letter-space movement being inclined with respect to the plane of movement of said member. 45
7. In type-writing machines, the combination with a power-propelled paper-carriage and with an escapement-rack therefor, of a reciprocating dog engaging the teeth of said rack, the opposing faces of said rack-teeth and of said dog in engagement at the end of the letter-space movement being inclined to the 50 plane of movement of said dog. 55
8. In type-writing machines, the combination with a power-propelled paper-carriage and with an escapement-rack therefor, of a reciprocating dog engaging said rack-teeth, said dog having two working, intersecting faces, both of which faces are inclined to the plane of its movement. 60
9. In a type-writing machine, the combination with a power-propelled paper-carriage and with an escapement-rack therefor, of a reciprocating dog engaging the teeth of said rack, each of said rack-teeth and said dog having two working, intersecting faces, all of which faces are inclined to the plane of movement of said dog. 65
10. In a type-writing machine, the combination with a power-propelled paper-carriage and with an escapement-wheel operatively connected thereto, of an escapement-dog arranged to swing across the path of the teeth 70 of said escapement-wheel, the faces of said teeth and of said dog opposed at the end of the letter-space movement being inclined to the plane of movement of said dog. 75
11. In a type-writing machine, the combination with a power-propelled paper-carriage and with an escapement-rack therefor, of a pair of rigidly-connected dogs arranged to swing transversely of said rack, said dogs being arranged in substantially the same plane 80 and having a transverse slot or opening between them, one of the dogs having a face engaging the teeth of said rack at the end of the letter-space movement, said face being inclined to the plane of movement of said dogs. 85
12. In a type-writing machine, the combination with an escapement-wheel and with a pair of dogs arranged to swing transversely of said wheel, of a rock-shaft whercon said dogs are mounted, a crank-arm connected to said 90 rock-shaft and another rock-shaft provided with crank-arms, one of which is connected by a link with the crank-arm of the rock-shaft that carries the escapement-dogs and the other of which is connected with the universal 95 bar, said link having a lost-motion, pin-and-slot connection with one of said crank-arms. 100
13. In a type-writing machine, the combination with a paper-carriage and with an escapement member therefor, of a universal bar, key-levers and a space-bar arranged to operatively engage said universal bar, the latter and said escapement member being independently spring-held and a free lost-motion connection between said universal bar and 105 said escapement member, whereby the vibration of said universal and space bars after returning to normal position, will not be transmitted to said escapement member. 110
14. In a type-writing machine, the combination with a paper-carriage and with a spring-held escapement member therefor, of a spring-held, pivoted universal bar independently spring-held pivoted key-levers and a spring-held, pivoted space-bar arranged to engage 115 said universal bar and a free, lost-motion pin-and-slot connection between said universal bar and said escapement member, whereby the vibration of said universal and space bars after returning to normal position is not transmitted to said escapement member. 120
15. In a type-writing machine, the combination with a spring-held escapement member and with a link operatively connected thereto, of a crank-arm operatively connected to the 125 universal bar, said crank-arm being interlocked with said link by a loose pin-and-slot lost-motion connection, whereby said escapement member is positively operated in one direction only. 130

16. In a type-writing machine, the combination with a spring-held escapement member and with a link operatively connected thereto and provided with a slotted end, of a crank-arm operatively connected to the universal bar and provided with a pin, said pin being in loose lost-motion engagement with said slot, whereby said escapement member is positively operated in one direction only.
- 10 17. In a type-writing machine, the combination with one of the transverse rods of the platen-frame, of an arm loosely pivoted on said rod, a presser-roll rotatably mounted upon the free end of said arm, a collar secured to said rod adjacent said arm, and a spring secured at one end to said collar and at the other end engaging said arm.
- 15 18. In a type-writing machine, the combination with one of the transverse rods of the platen-frame, of one or more arms loosely pivoted on said rod, a pair of presser-rolls independently mounted on the ends of each of said rods, and springs engaging the free ends of said rods intermediate each pair of presser-rolls.
- 20 19. In a type-writing machine, the combination with one of the transverse rods of the platen-frame, of arms loosely pivoted on said rod, a pair of independently-rotatable presser-rolls independently mounted on the ends of each of said arms, and springs secured to said rod and engaging the free ends of said arms intermediate each pair of presser-rolls.
- 25 20. In a "front-strike" type-writing machine, the combination with the platen, of an upwardly-curved and rearwardly-extending paper-guide plate mounted beneath said platen, openings in said paper-guide plate, the edges of which are turned away from the platen and spring-pressed rolls projected through said openings into engagement with the platen, substantially as described.
- 30 21. In a "front-strike" type-writing machine, the combination with a paper-carriage and with a vertically-shiftable platen mounted thereon, of a curved, paper-guide plate connected to and extending below said shiftable platen and an inclined paper-table mounted at the rear upon said paper-carriage and positioned above, normally in line with and closely adjacent the rear, upwardly-extending edge of said paper-guide plate.
- 35 22. In a type-writing machine, the combination with a movable paper-carriage and with a platen shiftably mounted thereon, of a paper-guide plate connected to and movable with the platen and a paper-table mounted upon and movable with the paper-carriage, and extending above and normally in line with said paper-guide plate, said paper-table and guide-plate having interlocking edges.
- 40 23. In a type-writing machine, the combination with a movable paper-carriage and with a platen shiftably mounted thereon, of a paper-guide plate connected to and movable
- 45 with the platen and a paper-table mounted upon and movable with the paper-carriage, and extending above and normally in line with said paper-guide plate, the adjoining edges of said paper-guide plate and said paper-table being interlocked and flanged outwardly.
- 50 24. In a type-writing machine, the combination with one of the rods of the platen-frame, of a bracket engaging one side of said rod, a U-shaped clamping-plate of spring metal to one arm of which said clamping-plate is attached and the other arm of which engages the opposite side of said rod and a pressure-roll and paper-guide carried by said parts.
- 55 25. In a type-writing machine, the combination with a grooved platen-frame rod, of a bracket engaging one side of said rod, a U-shaped clamping-plate of spring metal to one arm of which said bracket is secured, a tongue on the other arm of said U-shaped clamping-plate engaging the groove of said rod and a paper-guide and pressure-roll carried by said bracket and said clamping-plate.
- 60 26. In a type-writing machine, the combination with one of the rods of the platen-frame, of a bracket mounted on said rod, a presser-roll carried by said bracket, and a clamping-plate of spring metal for holding said bracket on said rod and having a portion acting to press said roll against the platen.
- 65 27. In a type-writing machine, the combination with one of the rods of the platen-frame, of a bracket mounted on said rod, a presser-roll carried by an arm pivoted to said bracket, and a clamping-plate for holding said bracket on said rod, said plate being extended at one end to form a paper-guide and provided at the other end with a tongue engaging said pivoted arm for holding the roller into and out of engagement with the platen.
- 70 28. In a type-writing machine, the combination with one of the rods of the platen-frame, of presser-rolls, pivoted frames wherein said presser-rolls are journaled, suitable bearings for said presser-roll frames mounted upon said rod, and springs whereby said presser-roll frames are held in and out of working position, said springs having extended portions partially encircling the platen.
- 75 29. In a type-writing machine, the combination with a paper-carriage and with a vertically-shiftable platen-frame pivoted at the rear to said paper-carriage, of mechanism for shifting said platen-frame, and a pair of counter-balancing-springs, one arranged at each side of the paper-carriage and intermediate the latter and the free end of said pivoted platen-frame.
- 80 30. In a type-writing machine, the combination with the platen and its supporting-frame, of means for shifting said parts from "lower-case" to "upper-case" position, comprising a rock-shaft connected with said platen-frame, an "upper-case" key-lever connected with said rock-shaft and means whereby said

rock-shaft may be shifted independently of said "upper-case" key-lever, said means comprising a supplemental shaft or rod extending through the main casing and provided at its outer end with a turning device and provided at its inner end with means for actuating the rock-shaft that is connected to the platen-frame.

31. In a type-writing machine, the combination with the platen-frame and platen and with means whereby said parts are shifted by the "upper-case" key-lever, of supplemental mechanism for shifting said platen and its frame from "lower-case" to "upper-case" position, comprising a short shaft or bar extending outside the main frame and provided at its outer end with a turning device and provided at its inner end with means by which movement may be imparted to the mechanism whereby the shifting of the platen-frame and platen is effected.

32. In a type-writing machine, the combination with the platen and its frame and with the rock-shaft connected with said platen-frame for shifting it from "lower" to "upper" case position, of a short shaft also connected to said rock-shaft and provided with crank-arms and a supplemental shaft provided at its outer end with a turning device and at its inner end with a crank-arm adapted to rock said short shaft in order to effect the shift of the platen and its frame.

33. In a type-writing machine, the combination with the platen and its frame and with the rock-shaft connected with said platen-frame for shifting said parts from "lower-case" to "upper-case" position, of a link 158 connected to said rock-shaft, a short shaft 160 provided with crank-arms 159 and 170, the

crank-arm 170 being united to the shaft 160 by a pin-and-slot connection, an "upper-case" key-lever connected with the crank-arm 170 and a supplemental shaft 161 provided with a crank-arm adapted to engage the crank-arm 159 in order to effect the shift of the platen and its frame independently of the "upper-case" key-lever.

34. In a type-writing machine, the combination with the platen and its frame and with mechanism connected with said platen-frame whereby it may be shifted from "upper-case" to "lower-case" position through the medium of the "upper-case" key-lever, a supplemental mechanism for shifting said platen comprising a shaft having a turning device at its outer end and having its inner end provided with means for engaging the mechanism whereby the platen is shifted, an arm connected with said supplemental shaft and a spring connected with said arm and serving to hold the supplemental shaft after the same has been turned to shift the platen from "upper-case" to "lower-case" position.

35. In a type-writing machine, the combination with a platen and with its supporting-frame, of mechanism for shifting said parts, a shift-key for said mechanism, a supplemental device independent of said shift-key for operating said mechanism comprising a rock-shaft having an operating thumb-piece, a rock-arm on said shaft arranged to engage said mechanism and a spring connected to said rock-shaft and arranged to hold said arm both in and out of operative position.
